PORTABLE SUPPORT FRAME FOR AN ELECTRICAL GENERATOR

Ernie Pastor, Marengo Township, Calhoun County, Mich., assignor to Epcos Mobilehome Products, Inc., Marshall, Mich., a corporation of Michigan

Application July 1, 1959, Serial No. 56,610

Term of patent 14 years

(Cl. D26—5)

I claim:

The ornamental design for a portable support frame for an electrical generator, as shown.
